UNITED STATES PATENT OFFICE.

JAMES E. MARSHALL AND THEODOR J. VOLZ, OF CANEY, KANSAS.

AUTOMOBILE LOCK AND SIGNAL.

1,297,214.

Specification of Letters Patent. Patented Mar. 11, 1919.

Application filed December 29, 1917. Serial No. 209,513.

To all whom it may concern:

Be it known that we, JAMES E. MARSHALL and THEODOR J. VOLZ, citizens of the United States, residing at Caney, in the county of Montgomery and State of Kansas, have invented new and useful Improvements in Automobile Locks and Signals, of which the following is a specification.

This invention relates to signal and locking mechanisms for motor vehicles.

The invention proposes the use of an adjustable plate bearing the owner's name, normally exposed to view and covering an immovable plate bearing the words "Owner out" or some similar expression; also means for locking said adjustable plate and through the medium of which the plate may be adjusted; also, the utilization of the adjustable plate to form part of a circuit breaking element under the control of a suitable lock mechanism, so that when said element assumes a position to break the ignition circuit, the adjustable or name plate is also moved to a position to uncover the immovable plate to expose to view the indicia thereon, and thereby indicate that the owner of the machine is absent therefrom.

In carrying out the invention we further make use of an electric bulb for illuminating the immovable plate at night time, the bulb being connected in circuit with a switch, of which the circuit breaking element forms a part, the latter being disposed to make contact with the stationary part of the switch when the said element assumes a position to break the ignition circuit, thus lighting the bulb through the instrumentality of which the plate bearing the words "Owner out" or some other similar expression is illuminated.

Other objects of importance will appear as the nature of the invention is better understood from the following detail description taken in connection with the accompanying drawings, the invention residing in the construction, combination and arrangement of parts as claimed.

In the drawings forming part of this specification like numerals of reference indicate similar parts in the several views and wherein:

Figure 1 is a fragmentary side elevation of a motor vehicle showing the invention associated therewith.

Fig. 2 is a sectional view taken on line 2-2 of Fig. 1.

Fig. 3 is an enlarged diagrammatic view of the invention showing the normal position of parts.

Fig. 4 is a similar view showing the position of parts when the ignition circuit is broken.

Fig. 5 is a view similar to Fig. 1 and showing the plate 10 by dotted lines in the lowered position.

Referring to the drawings in detail and particularly to Figs. 3 and 4, 10 indicates a plate bearing the name of the owner of the motor vehicle with which the invention is used. The plate 10 forms a part of a combined circuit breaking and making element, which in addition to the plate 10 includes an arm 11 pivoted at a suitable point in its length as at 12. The free extremity of the arm 11 carries a contact 13 which is adapted to be moved with the arm toward and away from a fixed contact 14, co-operating with the latter to make and break the ignition system of the motor vehicle, the wire 15 leading to the starting and ignition switch of the machine, while the wire 16 leads to the storage battery. The combined circuit making and breaking element normally rests in the position illustrated in Fig. 3 with the contact 13 engaging the contact 14, in which position of parts the machine may be manipulated or run. Any suitable lock mechanism may be employed for maintaining the combined circuit making and breaking element in this position, use however being made of a key actuated lock indicated at 17. However when it is desired to prevent theft of the car during the owner's absence therefrom the lock is actuated to release the combined circuit making and breaking element to permit the latter to assume the position illustrated by full lines in Fig. 4, and by dotted lines in Fig. 5 wherein the contacts 13 and 14 respectively are separated and the ignition circuit broken, which obviously prohibits use of the car.

A plate 18 of a size and configuration conforming to the plate 10 is also embodied in the invention, and bears the words "Owner out" or some other similar expression, to indicate the absence of the owner from the machine. It might here be stated that the device forming the subject matter of the invention may be installed between the metal panel and the inside lining of the car, preferably in the space between the doors on a

touring car, or in any other conspicuous place which would attract attention. As is shown in Figs. 1, 2 and 5 the metal paneling or body of the car is provided with an elongated slot 19 which is covered by a piece of glass, mica or some other transparent material as shown. The plate 18 is also arranged in the space between the metal paneling and the inside lining of the car, immediately at the rear of the slot 19, while interposed between the latter and the plate 18 is the plate 10. The plate 18 is also constructed from glass or some other suitable transparent material. The lock 17 is also arranged in the space between the paneling and the lining of the car. As hereinabove stated the plate 18 is immovable, and when the combined circuit making and breaking element is in its normal position such as shown in Figs. 1 and 3, the plate 10 thereof concealing the plate 18 from view, being disposed immediately in advance of the latter. However when the said element is released and moved to a position to break the ignition circuit, the plate 10 assumes the position illustrated by full lines in Fig. 4, and dotted lines in Fig. 5, at which time the plate 18 is exposed to view through the slot 19.

As mentioned above, the plate 18 is constructed from some suitable transparent material, and in order to render the same quite noticeable at night time, the plate 18 is illuminated through the instrumentality of an electric bulb 20. The bulb is connected in circuit with a stationary switch element 21 the latter in turn being connected by a wire 22 to the wire 16 which leads to the storage battery. Fixed upon the free extremity of the arm 11 is a contact 23 forming a component part of the switch with which the electric bulb is connected in circuit. The disposition of parts is such that when the combined circuit making and breaking element assumes the position shown in Fig. 4, breaking the ignition circuit, the contact 23 is brought into engagement with the switch element 21 closing the circuit to the bulb 20 for the purpose of illuminating the plate 18. The invention is not only efficient for the purpose intended, but it is simple in construction and can be installed upon any make of car.

It is desired to have it understood that what has been herein shown and described is merely illustrative of one and the preferred embodiment of the invention to

which we do not limit ourselves, and that such changes may be resorted to when desired as fall within the scope of what is claimed.

What is claimed is:—

1. A combined signal and circuit breaker for automobiles having a slot in the body thereof, a pivoted element disposed in the space between the metal paneling and lining of the car, a signal registering with said slot and indicative of the owner's absence from the car, key actuated means for locking said element normally in a position to complete the circuit, and to conceal the signal from view, said element gravitating to a position to break said circuit and expose the signal, and said element being returned to active position through the instrumentality of the key.

2. A combined signal and circuit breaker for automobiles having a slot in the body thereof, an element pivoted upon the inside of the metallic paneling and included in the ignition circuit, a signal disposed in registration with said slot for indicating the owner's absence from the car, means for locking said element in a position to complete the circuit and to conceal the signal from view, said element gravitating when released to a position out of reach, to expose said signal, a lamp circuit, and said element completing the latter mentioned circuit when in its ignition circuit breaking position to illuminate said signal.

3. An outer wall of the vehicle body having a display opening, a plate arranged in spaced relation back of said wall and in registration with said opening and bearing the words "Owner out" or a word or device of analogous import, a swinging plate movable back of said wall and to and from a position in front of the plate, said plate gravitating when released to a position out of reach to expose said signal, a lock mounted in the wall and connected to the swinging plate and through which the plate is swung to position to hide the first named plate or signal, electric means for illuminating the first named plate, and means operated by gravitation of the swinging plate for putting said illuminating means into operation and displaying the first named plate.

In testimony whereof we affix our signatures.

JAMES E. MARSHALL.
THEODOR J. VOLZ.
